[57] CLAIM

The ornamental design for a simulative picture frame, as shown and described.

DESCRIPTION

FIG. 1 is a front perspective view of a simulative picture frame showing my new design, the side opposite being substantially a mirror image;

FIG. 2 is a front elevational view of a fragment of the claimed design showing a handle member on an enlarged scale;

FIG. 3 is a top plan view thereof;

FIG. 4 is a top plan view of a portion of the claimed design.
